UNITED STATES PATENT OFFICE.

JOHN N. HAHN, OF CLEVELAND, OHIO.

MACHINE FOR FACING CORRUGATED PAPER.

1,151,681.

Specification of Letters Patent. Patented Aug. 31, 1915.

Application filed June 5, 1911. Serial No. 631,205.

To all whom it may concern:

Be it known that I, JOHN N. HAHN, a citizen of the United States, and a resident of the city of Cleveland, county of Cuyahoga, 5 and State of Ohio, have invented certain new and useful Improvements in Machines for Facing Corrugated Paper, of which the following is a specification.

This invention relates to machines for applying facing strip or sheet to crimped or corrugated paper.

It has come to be well known that if a sheet of paper is corrugated and other sheets applied as facings by pasting the same to 15 the crowns of the corrugations, a board is obtained which is not only comparatively stiff and strong, but which is exceedingly light in weight, and therefore provides a most desirable material for packages in 20 which to ship goods of various kinds.

There are many well-known forms of machines for corrugating paper and applying one or more facing strips thereto. To produce this so-called cellular board, the more 25 common process, briefly described, consists in corrugating a strip or web of paper, applying paste to the crowns of the corrugations, feeding a facing strip against the corrugated strip and holding the same in contact therewith until the paste had set or 30 dried. The process may be continuous or intermittent, and after the facing strip or strips have adhered to the corrugated strip, the web or strip is cut into sheets of a certain 35 tain length to be subsequently made into boxes or packages, or used in other ways.

Machines for carrying out a continuous corrugating and facing process usually comprise means for carrying the pasted corrugated strip with the facing strip applied thereto between plates or rollers or other means for retaining them in close contact with each other until the paste has set or 40 dried. The drying operation is almost always facilitated by the application of heat, the plates or rollers which keep the strips in contact with each other being themselves heated, or the entire drying process being carried on in a heating chamber.

50 It will be apparent that where upper and lower plates are employed to hold the strips in contact with each other, these plates must be so spaced apart as to create a decided pressure against the paper strips, thus generating no small amount of friction which

must be overcome in advancing the strips through the machine. Herein is the most difficult problem which confronts the manufacturer of double-faced corrugated paper, that being the apparent necessity of employing friction or feed rollers—or other frictional conveying means—to advance the strips, the pressure necessarily exerted upon the paper between these rollers, to secure sufficient friction to draw the paper between 60 presser plates of proper length, being sometimes so great as to at least partially crush the corrugations and thus weaken the board. Therefore, a certain amount of heating and drying surface and a certain 65 amount of the desired pressure must be sacrificed, as a rule, on account of the fact that the friction must not be so great but what the feed rollers will grip and advance the strips without the application of a destructive 70 pressure.

It must be taken into consideration that to produce a uniform product by a "continuous" process, first, the facing strip or strips must be held against the corrugated 75 strip with sufficient pressure to cause contact throughout the entire extent of the crowns of the corrugations to which the paste has been applied; second, that these pasted strips must be advanced subject to 80 such pressure, and, third, that the advancing means must not grip the strips with sufficient force to crush the corrugations. These requirements have necessitated the 85 generation and application of a high degree 90 of heat to hasten the drying operation, in order that the distance through which the strips are drawn under pressure may be made a minimum and thus reduce friction to the lowest possible point, whereby a gripping pressure of lesser degree may be applied to advance the strips. Furthermore, 95 it not infrequently happens that in the effort to reduce this friction, insufficient pressure is applied to the pasted strips and the resulting product, therefore is not uniform 100 and is oftentimes otherwise imperfect.

The principal objects of the present invention are, first, the provision of a machine in which a yielding but positive and substantially uniform pressure is directed 105 against the advancing pasted strips during the drying operation; second, the provision of improved means for continuously advancing the strips under such conditions 110

without destructive pressure, whereby a more uniform and perfect product may be produced; third, to effectively combine the pressing and advancing means, thereby not 5 only reducing friction and economizing power, but also materially decreasing the usual excessive length of a machine of this character; fourth, to provide both pressing and advancing means which are automatically self-adjustable to slight variations in the heights of the corrugations, and, fifth, to provide a machine which is exceedingly simple in construction and operation, which can be operated at small cost and produce a 10 uniform and high grade product.

My invention will be more readily understood by reference to the accompanying drawings, forming a part of this specification, in which—

20 Figure 1 is a side elevation of a complete machine embodying my invention; Fig. 2 is an enlarged rear end view thereof with the cutting mechanism omitted; Fig. 3 is a longitudinal section of a portion of the pressing and advancing means, taken substantially on the line 3—3 of Fig. 2, and Fig. 4 is an enlarged detail view hereinafter described.

Processes of corrugating paper strips and 30 applying a facing strip to each side of the corrugated strip, referring now to processes in which the strips are continuously advancing through the machine, are of two general kinds; one in which a single machine is de- 35 signed to corrugate one strip and apply both facing strips thereto, and the other in which a single facing strip is applied to the corrugated strip and this single-faced corrugated strip is rolled upon a reel to be sub- 40 sequently fed into a machine for applying the second facing strip. Each of these processes possesses certain advantages over the other, the former, for instance, being the more rapid and doubtless effecting a certain 45 saving in heat and power, and the latter probably producing a superior product, inasmuch as when the crowns of the corrugations on both sides of the corrugated strip are saturated with the pasting solution at 50 substantially the same time, the rigidity of the corrugated strip is impaired and it is more difficult to preserve the corrugations in their original form. Furthermore, it will be apparent that when the comparatively green 55 single-faced strip is received from the corrugating and single-facing machine, in rolling the same upon a reel the paste is given an opportunity to become thoroughly set and the paper stock perfectly dry, with the 60 roll itself keeping the facing strips under the necessary pressure to preserve substantially uniform contact between the facing strip and the crowns of the corrugations on one side of the corrugated strip. For the 65 above and other reasons, I prefer to corru-

gate a sheet in any one of the many well known ways and apply a single facing strip thereto, rolling the single-faced strips on a reel, as suggested, and subsequently mounting this roll in position to feed the strip 70 therefrom into the machine for applying the second facing strip.

Referring now to the drawings in detail, 75 numeral 11 refers to a roll of a single-faced corrugated paper, as the same has been received from the corrugating and single-facing machine, which roll is preferably mounted upon a spindle 12 carried by the movable frame 13, which is mounted upon rollers or casters 14 in order that the same may be 80 readily transferred from place to place and readily adjusted in position to direct the strip 15 from said roll through the pasting mechanism, hereinafter described, and into the double-facing machine.

85 The double-facing machine proper comprises a box or casing 16, suitably supported at a proper height by the legs 17. Upon this box or casing are mounted a plurality of hollow plates 18, the upper faces of which 90 provide a support for the moving corrugated strip which is being faced, being, therefore, level and smooth.

Journaled in bearings in the brackets or standards 19 supported upon the rails 20 at 95 the sides of the machine, are a plurality of rollers 21. These rollers are hollow and flexible, and therein resides one of the most important features of the present invention. Each of these rollers 21 comprises an axle 100 22, carrying near each end thereof a disk 23. To the peripheries of these disks are secured the ends of the flexible tube 24, which is made of material such as canvas or other fabric which has been treated in any one of many well-known ways to make the same air-tight. This flexible tube or cylinder 24 is, of course, secured to the disks 23 in such a manner as to insure an air-tight joint, as by providing the binding strap 25. These 105 hollow rollers are kept filled with air under pressure, in a manner hereinafter described, and the axles 22 are so located with respect to the plates 18 that the major middle portion of the bottom of each roller is flattened 110 to a substantial extent by the pressure against said plates, as shown (somewhat exaggerated, to better illustrate the invention) in the drawings, whereby a comparatively large area of the material of which the cylindrical portion of the roller is made will 115 contact with the face of one or more of the plates 18, or with the paper strips therebetween. The dimensions of the roller being reduced by this distortion, it will be apparent that the air pressure therein will be increased, and will cause the flattened side of 120 said roller to be firmly pressed against the plate or plates 18.

125 Mounted upon a table, stand or suitably 130

supported frame 26, at the front end of the machine, is the paste-pot 27 into which dips the paste-roller 28, rotated in the manner hereinafter described. Immediately above 5 this paste-roller 28, is the idler-roller 29, adapted to bring the crowns of the corrugations of the corrugated strip, passing thereunder, into contact with the paste-roller. The reel or spool 30 of the roll 31 of paper 10 which is to provide the second facing strip, is preferably journaled in bearings in the standards 32, which are so positioned as to deliver the strip from said roll around the idler roller 33 journaled in said frame 26. The 15 single-faced corrugated strip from the roll 11 is directed under the idler roller 29, where a small quantity of paste is delivered to each of the crowns of the corrugations by the paste-roller 28. The facing-strip from 20 the roll 31 and the single-faced corrugated strip to which the paste has been applied are both carried over the plates 18 and underneath the rollers 21. Each of the axles 22 of the rollers 21 is provided with a sprocket 25 wheel 36, around which passes the chain 37 to rotate said rollers at a uniform velocity. The axle of any one of the rollers 21 may be directly coupled to a source of power, as, for instance, through the pulley 38, and thus 30 drive the chain 37, thereby rotating the other rollers 21 in the same direction and at the same velocity. The axle of the front roller 21, in addition to the sprocket wheel 36, is provided with a sprocket wheel 39, 35 which drives the pasting roller 29 through the chain 40 which passes around the sprocket wheel 39 and the sprocket wheel 41 on said pasting roller.

Between each pair of the plates 18, I prefer 40 to mount an anti-friction roller 42, which rollers may be idlers or each of which may be provided with a sprocket wheel 43 (one thereof being shown in Fig. 2) whereby said rollers may be rotated in unison by a chain 45 passing over or around said sprockets. These rollers are intended to reduce the friction between the moving strips and the plates 18, and the upper ends of said plates adjacent to said rollers are preferably curved, as 50 shown, to make the combined upper surface of said plates as nearly continuous as possible.

It will be apparent that the material of 55 which the cylindrical portions of the rollers 21 are made, and the large area of contact surface provided by the flattening of these rollers, will insure a large gripping surface the internal air pressure holding the flattened face of the roller in positive and 60 substantially uniform contact with the strips of paper underneath the same. The character of the material and the yielding nature of the pressure are such that the roller will grip the strips and upon rotation advance 65 the same under a pressure which, while suffi-

cient to keep the pasted strips in uniform contact with each other and advance said strips, is not sufficient to crush the corrugations, as is so likely to happen when solid rollers are employed, where the area of contact is so small that the pressure must be proportionately increased and is of a substantially unyielding character. It will be found that a comparatively very large area of the upper face of the paper underneath 70 the rollers 21 may be made to contact with the flattened faces of the rollers, and, the plates 18 being smooth and friction still further lessened by provision of the rollers 42, the pasted strips will be advanced over 75 the plates 18 with the application of comparatively but little power, and at the same time the pasted strips will be held in substantially uniform contact with each other during the drying process.

Particular attention is directed to the fact that the stock from which this corrugated paper is made varies in quality and thickness, on account of which, and for other reasons, the corrugations are not invariably 80 of the same height, even in a single strip or web. On this account, where solid or unyielding rollers, or other rigid advancing means, are employed, not even the most careful adjustment can insure against either 85 unduly crushing the crowns of the higher corrugations or perfect adhesion of the facing strip or strips to the crowns of the lower corrugations. It will be apparent that the 90 yielding character of my flexible roller insures automatic-self-adjustment to corrugations of heights which vary even in a single strip or web, the air pressure within the cylinder insuring substantially uniform compression of the facing strip against the 95 pasted crowns of the corrugations in the corrugated strip, irrespective of any slight variations in the heights of the corrugations.

In order to facilitate the drying operation, I prefer that the plates 18 shall be 100 heated, and also prefer to heat the rollers 21 to a lesser degree by means of hot air. The frame 16 provides a chamber into which I direct the steam pipe 44, this pipe having 105 branches 45 which direct the steam into the 110 interior of the hollow plates 18 to heat said plates. The incasing of these steam pipes within the chamber provided by the frame 16, will heat the air in said chamber, from 115 which the heated air is withdrawn through the pipe 56 by the air-pump 47 and forced through the pipe 48 and its branches 49 to the interior of the rollers 21. The axle of each of said rollers at this side of the machine is hollow to permit of the well-known 120 form of connection to direct the air into the interior of said roller. In this manner, not only may the plates 18 be heated to a comparatively high degree, but the rollers may 125 be heated by the air employed to keep them 130

in an inflated condition to still further hasten the drying operation.

When the double-faced corrugated strip is delivered from the rear end of the machine 5 it may be readily severed into sheets of any desired lengths in any one of many well-known ways, as by the shearing knives 50 50.

Many modifications of minor details of my improved machine for double facing corrugated paper will doubtless readily suggest themselves to those skilled in the art to which it appertains, and I, therefore, do not desire to limit my invention to the specific construction herein shown and described:

I claim as new and desire to secure by Letters Patent:

1. In a machine of the character described, the combination, with means for directing a corrugated strip with and between plain facing strips into the machine, and means for applying an adhesive to crowns of the corrugations, of a stationary flat support for the advancing strips, and a movable and elastically distortable member co-operating with said support to frictionally advance the superposed strips under pressure therebetween.

2. In a machine of the character described, the combination, with means for directing a corrugated strip with and between plain facing strips into the machine, and means for applying an adhesive to crowns of the corrugations, of a stationary flat support for the advancing strips, and a rotatable and elastically distortable member co-operating with said support to frictionally advance the superposed strips under pressure therebetween.

3. In a machine of the character described, the combination, with means for directing a corrugated strip with and between plain facing strips into the machine, and means for applying an adhesive to crowns of the corrugations, of a stationary flat support for the advancing strips, and a rotatable and elastically distortable member co-operating with said support to frictionally advance the superposed strips under pressure therebetween.

4. In a machine of the character described, the combination, with means for directing a corrugated strip with and between plain facing strips into the machine, and means for applying an adhesive to crowns of the corrugations, of a stationary flat support for the advancing strips, and a series of rotatable and elastically distorted members co-operating with said support to frictionally advance the superposed strips under pressure therebetween.

5. In a machine of the character described, the combination, with means for directing a corrugated strip with and between plain facing strips into the machine, and

means for applying an adhesive to crowns of the corrugations, of a stationary flat support for the advancing strips, and a hollow, partly flexible and inflated member movable to frictionally advance the superposed strips under pressure between the flexible portion of said member and said support.

6. In a machine of the character described, the combination, with means for directing a corrugated strip with and between plain facing strips into the machine, and means for applying an adhesive to crowns of the corrugations, of a stationary flat support for the advancing strips, and a series of hollow, partly flexible and inflated members movable to frictionally advance the superposed strips under pressure between the flexible portions of said members and said support.

7. In a machine of the character described, the combination, with means for directing a corrugated strip with and between plain facing strips into the machine, and means for applying an adhesive to crowns of the corrugations, of a stationary flat support for the advancing strips, and a hollow, partly flexible and inflated member rotatable to frictionally advance the superposed strips under pressure between the flexible portion of said member and said support.

8. In a machine of the character described, the combination, with means for directing a corrugated strip with and between plain facing strips into the machine, and means for applying an adhesive to crowns of the corrugations, of a stationary flat support for the advancing strips, and a series of hollow, partly flexible and inflated members rotatable to frictionally advance the superposed strips under pressure between the flexible portions of said members and said support.

9. In a machine of the character described, the combination, with means for directing a corrugated strip with and between plain facing strips into the machine, and means for applying an adhesive to crowns of the corrugations, of a stationary flat support for the advancing strips, and a rotating member presenting a normally cylindrical and elastically yielding contact surface to said support and being flattened by pressure against the superposed strips between said surface and said support, and means for rotating said member.

10. In a machine of the character described, the combination, with means for directing a corrugated strip with and between plain facing strips into the machine, and means for applying an adhesive to crowns of the corrugations, of a stationary flat support for the advancing strips, and a series of rotating members each presenting a normally cylindrical and elastically yielding contact surface to said support and be-

ing flattened by pressure against the superposed strips between said surface and said support, and means for rotating said members in unison.

5 11. In a machine of the character described, the combination, with means for directing a corrugated strip with and between plain facing strips into the machine, and means for applying an adhesive to

10 crowns of the corrugations, of a stationary flat support for the advancing strips, a hollow rotating member presenting a normally cylindrical, flexible and inflated contact surface to said support and being elastically flattened by pressure against the superposed strips between said surface and said support, and means for rotating said member.

15 12. In a machine of the character described, the combination, with means for directing a corrugated strip with and between plain facing strips into the machine, and means for applying an adhesive to crowns of the corrugations, of a stationary flat support for the advancing strips, a series of hollow rotating members each presenting a normally cylindrical, flexible and inflated contact surface to said support and being elastically flattened by pressure against the superposed strips between said

20 surface and said support, and means for rotating said members in unison.

25 13. In a machine of the character described, the combination, with a stationary plate, of a hollow presser member having a flexible portion adapted to contact with said plate, means for heating said plate, means for directing a heated fluid to the interior of said member and retaining the same under pressure therein, and means for driving

30 said member, for the purpose specified.

35 14. In a machine of the character described, the combination, with a stationary plate, of a member having a normally cylindrical portion of flexible material pressing against said plate and being distorted thereby, means for heating said plate, means for directing a heated fluid to the interior of said member and retaining the same under pressure therein, and means for rotating

40 said member.

45 15. In a machine of the character described, the combination, with means for directing a corrugated strip with and between plain facing strips into the machine, and means for applying an adhesive to crowns of the corrugations, of a stationary plate, a hollow presser member having a flexible portion adapted to contact with said plate, means for directing a heated fluid to the interior of said member and retaining the same under pressure therein, and means for driving said member.

50 16. In a machine of the character described, the combination, with means for directing a corrugated strip with and be-

tween plain facing strips into the machine, and means for applying an adhesive to crowns of the corrugations, of a stationary plate, a member having a normally cylindrical portion of flexible material pressing against said plate, means for directing a heated fluid to the interior of said member and retaining the same under pressure therein, and means for rotating said member.

55 17. In a machine of the character described, the combination, with a suitable stationary plate, of a series of hollow presser members, each having a flexible portion adapted to contact with said plate, means for heating said plate, means for directing a heated fluid to the interior of said members and retaining the same under pressure therein, and means for rotating said members.

60 18. In a machine of the character described, the combination, with a stationary plate, of a series of hollow members each having a normally cylindrical portion of flexible material pressing against said plate and being distorted thereby, means for heating said plate, means for directing a heated fluid to the interior of each of said members and retaining the same under pressure therein, and means for rotating said members.

65 19. In a machine of the character described, the combination, with means for directing a corrugated strip with and between plain facing strips into the machine, and means for applying an adhesive to crowns of the corrugations, of a stationary plate, a series of hollow presser members each having a flexible portion adapted to contact with said plate, means for directing a heated fluid to the interior of each of said members and retaining the same under pressure therein, and means for driving

70 said members.

75 20. In a machine of the character described, the combination, with means for directing a corrugated strip with and between plain facing strips into the machine, and means for applying an adhesive to crowns of the corrugations, of a stationary plate, a series of members each having a normally cylindrical portion of flexible material pressing against said plate and being flattened thereby, means for heating said plate, means for directing a heated fluid to the interior of said members and retaining the same under pressure therein, and means for rotating said members.

80 21. In a machine of the character described, the combination, with a series of stationary plates with anti-friction rollers therebetween to provide a substantially continuous flat support, of a series of rotating members presenting elastically yielding contact surfaces to said support and being distorted thereby, and means for rotating said

- members, each anti-friction roller being located immediately below one of said rotating members.
22. In a machine of the character described, the combination, with means for directing a corrugated strip with and between plain facing strips into the machine, and means for applying an adhesive to crowns of the corrugations, of a series of 10 stationary plates with anti-friction rollers therebetween to provide a substantially continuous flat support, a series of members each having a normally cylindrical and elastically yielding portion pressing against said 15 support and being flattened thereby, and means for rotating said members, each of said anti-friction rollers being located immediately below one of said rotating members.
- 20 23. In a machine of the character described, the combination, with means for directing a corrugated strip with and between plain facing strips into the machine, and means for applying an adhesive to 25 crowns of the corrugations, of a series of stationary plates with anti-friction rollers therebetween to provide a substantially continuous flat support, a series of hollow members each having a normally cylindrical portion of flexible material pressing against 30 said support and being distorted thereby, means for inflating said members and retaining the same in an inflated condition, and means for rotating said members in 35 unison, each of said anti-friction rollers be-
- ing located immediately below one of said rotating members.
24. In a machine of the character described, the combination, with a series of stationary plates and anti-friction rollers 40 therebetween to provide a substantially continuous support, of a series of hollow presser members each having a flexible portion adapted to contact with said plates, means for heating said plates, means for directing 45 a heated fluid to the interior of said members and retaining the same under pressure therein, and means for rotating said members.
25. In a machine of the character de- 50 scribed, the combination, with a series of stationary plates and anti-friction rollers therebetween to form a substantially continuous support, of a series of hollow members each having a normally cylindrical por- 55 tion of flexible material pressing against said support and being distorted thereby, means for heating said plates, means for directing a heated fluid to the interior of each of said members and retaining the same 60 under pressure therein, and means for rotating said members.

In testimony of the foregoing, I have hereunto set my hand in the presence of two witnesses.

JOHN N. HAHN.
